CASTER BRAKE

Anthony C. Libhart, Craighead, Ark., assignor to The Colson Corporation, Chicago, Ill., a corporation of Illinois

Filed Aug. 29, 1967, Ser. No. 8,423

Term of patent 14 years

(Cl. D10—6)

The broken lines are for illustrative purposes only.

I claim:

The ornamental design for a caster brake, as shown and described.
